UNITED STATES PATENT OFFICE.

ADOLPH H. SCHLUETER, OF SAN FRANCISCO, CALIFORNIA.

LIGHTING DEVICE FOR LAMPS.

SPECIFICATION forming part of Letters Patent No. 270,849, dated January 16, 1883.

Application filed July 7, 1882. (No model.)

To all whom it may concern:

Be it known that I, ADOLPH HENRY SCHLUETER, of the city of San Francisco, in the county of San Francisco and State of California, have 5 made a new and useful Improvement in Lighting Devices for Lamps, &c.; and I do hereby declare that the following is a full, clear, and exact description of the same, reference being had to the accompanying drawings, forming a 10 part of this specification, in which—

Figure 1 is a side view of a lamp-burner embodying my improvement. Fig. 2 is a view, partly in section and partly in side view, thereof; and Fig. 3 is a horizontal section of the 15 same.

This invention relates to improvements in devices for lighting lamps, lamp-stoves, or other medium for producing light or generating heat by coal-oil or other oil, and has for its 20 object to effect the convenient and ready lighting of the same without requiring the removal of the chimney or other fixtures, or the person standing in an elevated position where the lamp is suspended from a ceiling or otherwise 25 supported out of convenient reach.

The nature of this invention consists in combining with a wick-tube an oil-absorbent adapted to absorb the oil of its wick, and to extend a greater or less distance therefrom, 30 by which the lighting operation may be performed by simply applying the ignited match or flame to the outer end of said absorbent, substantially as hereinafter more fully set forth and claimed.

In carrying out my invention I employ, in connection with the wick-tube A of a lamp-burner or oil-stove or other medium for producing light or generating heat by coal-oil or other oil, the device B, to permit the convenient and ready lighting of its wick, as presently explained. The lighting device B is made of some material which will act as an absorbent of the oil of the wick—as, for instance, asbestos—and disposed along a strip 45 of metal or brass, a. The strip of metal or brass a having the absorbent is adapted to extend to the wick-tube A, to a point contiguous to the upper end of the tube, where it is carried, with the absorbent, through the tube 50 to bring the absorbent into contact with the

wick, to allow the saturation thereof with the oil of the wick. The strip of metal a, with the absorbent, is extended outward from the wick-tube and downward through the burner to a convenient point below, to permit it to be 55 readily reached without requiring the person to use a chair or other temporary elevated standing-point. The absorbent is caused to descend a little below the outer end of the strip of metal or support a, to allow the flame 60 or ignited match to be readily applied thereto.

It will be noticed that, the absorbent on the plate a being saturated with the oil taken from the wick, it will, by applying the flame or ignited match thereto, transmit a flame along 65 its surface to the upper end of the wick, and thus transfer the flame to the wick, effecting the lighting of the same. It will feed its flame sufficiently long at its upper or wick-tube end to allow time for elevating the wick in the 70 event the latter should be below the upper end of its tube. It is also capable of extinguishing itself by reason of the consumption of its supply of oil by combustion after the lighting of the wick. It will again supply it- 75 self with oil, ready to be relighted when desired.

It will be further observed that the lighting operation can be performed without requiring the removal of the chimney or other fixtures, 80 while the great difficulty heretofore experienced in lighting oil-stoves is avoided.

The device B, by providing it with branches or arms arranged in a similar manner as its upwardly-extended portion, is adapted to be 85 used with a lamp or oil-stove having a series of wick-tubes or burners.

It will also be understood that, instead of feeding the absorbent with oil from the wick, it may be fed directly from the vessel containing the oil by providing the absorbent with a branch or arm adapted to extend down into the oil-vessel.

Having thus described my invention, what I claim, and desire to secure by Letters Patent, 95 is—

1. The combination, with a wick-tube, of a lighting device having an absorbent adapted to take the oil from the wick and to transmit it throughout its surface, and extended a con- 100

venient distance therefrom, substantially as and for the purpose set forth.

2. The combination, with a wick-tube, of the lighting device B, having the absorbent or asbestos, and the support *a*, extended to a point contiguous to the upper end of the wick-tube and through it, and thence outward and down-

ward, (or upward,) substantially as and for the purpose set forth.

ADOLPH HENRY SCHLUETER.
